EUGENE D. CHELLIS, OF PORTLAND, MAINE, ASSIGNOR, BY MESNE ASSIGNMENTS, TO NATIONAL METAL SEAL CORPORATION, A CORPORATION OF MAINE.

CAP FOR BOTTLES.

1,033,081.

Specification of Letters Patent. Patented July 23, 1912.

Application filed October 9, 1907. Serial No. 396,530.

To all whom it may concern:

Be it known that I, EUGENE D. CHELLIS, a citizen of the United States, residing at Portland, county of Cumberland, State of Maine, have invented certain new and useful improvements in Caps for Bottles, of which the following is a specification.

This invention has to do with the construction and arrangement of closures for containing vessels and particularly to closures of this sort in which a tight fit is desired to be maintained between the closure proper and the mouth of the bottle at all times. With most closures of this sort where a packing is to be employed difficulty is experienced in securing uniformity of contact and proper compression of the packing material. It is particularly necessary in closures intended to be used on liquid retaining receptacles to have the packing afford a close fit and leave no chance for the leakage or accumulation of the contents of the vessel between the cap proper and the bottle mouth. It is furthermore desirable to so arrange the cap that the delivery of the liquid will be made easy under all conditions and so that the flow will be uniform throughout.

To this end I have devised the subject matter of my present invention which involves the provision of suitable means for maintaining between the closure and the vessel mouth the proper relation by which the packing will be suitably compressed and held against displacements and changing in form, so that under such conditions as those surrounding the pouring of the liquid from the vessel the parts will remain with a uniform tight fit and the contents be delivered in a rapid and uniform manner.

In the structure which I have shown and described as an embodiment of this invention I have provided a means for holding the packing in suitable position and under a suitable pressure and have provided for the delivery of the contents in the manner desired by an arrangement of ports which I will now disclose.

In the drawings: Figure 1 is a top plan view of my bottle closure partially applied to the mouth of the bottle, Fig. 2 is a similar view, in section, Fig. 3 is a view of the closure in place on the bottle mouth, and, Fig. 4 is an enlarged detail section.

1 is a bottle neck having a shoulder 2 about its mouth.

7 is a cap plate having a depending marginal flange 8 and spring fingers 15 depending therefrom and adapted to engage the shoulder 2 of a bottle mouth.

18 is a cover having a locking lip 14 adapted to engage the shoulder of the bottle on the opposite side from its point of pivot to the cap plate which point of pivot is numbered 19.

41 are a pair of openings through the cap plate 7.

80 is a packing which is preferably of annular form and of suitable size to cover the mouth of the bottle and be contained within the depending flange 8.

70 is an annular depending compressing rib formed in the resilient metal of the plate about midway of that portion of the plate 7 which covers the surface of the bottle mouth.

The cover plate 18 has a central recess formed as a depression in the metal of the cover and located on the under side thereof. Within this depression is located a sealing pack 18¹, shown in Figs. 3 and 4 of the drawings. The depression and the pack located within the depression are of sufficient size to cover any opening or openings in the cap plate 7 so as to overlie the same and to be held down firmly thereon by the spring locking lip 14 which engages the under side of the shoulder 2 formed about the mouth of the vessel. It will be seen that the location of the pack in this recess protects the pack 18¹ against dislodgment by the lateral swing of the cover in case the cover be swung entirely off the plate 7. Nevertheless, when swung to cover the plate 7 the spring locking lip 14 will draw it down snugly so as to completely seal the openings in the pack.

The combination of the pack in the laterally swinging cover affords furthermore a peculiar combination in that the cover is not normally swung off when in ordinary use, but remains partly overlying the cap, so that the pack 18¹ is supported by the upper surface of the cap plate 7.

The closure is applied to the bottle in the usual manner, by slipping it transversely upon the mouth of the bottle while the cover plate 18 is opened so that the spring fingers 15 will engage with the shoulder 2 and draw the cap plate 7, when finally positioned, over the bottle mouth down on to the same, thus bringing the depending flange 8 over

the edge of the bottle mouth. When the plate 7 is being drawn down upon the bottle mouth by the spring fingers, the depending rib 70 bears into packing 80 and exerts 5 upon it a uniform pressure along an annular line running midway of the bottle mouth. This gives to the packing 80 a compression which affords completeness of contact completely around the mouth of the 10 vessel and, at the same time, holds the packing against displacement or changing shape due to any relative slipping of the parts. With the cap thus positioned the liquid may be poured from either of the openings 41. 15 When the bottle is completely filled only one of these openings is necessary and the swinging cap 18 may be left partially closed covering a portion of the plate 7, so that one opening will be closed. When it is de- 20 sired to pour rapidly in such a manner that air is needed to overcome the vacuum tendency in the bottom of the vessel both openings are left uncovered and when the openings are held so that one lies above the other 25 a uniform stream will be delivered from the lower opening, while the air supply is drawn from the opening above. In closing the vessel the cover 18 is swung to until the cap plate 7 is completely covered and the locking lip 14 engages the shoulder 2 opposite to its point of pivot.

Various modifications in the structure of the parts herein shown may be made without departing from the subject of my invention. It is obvious that the nature of the 35 openings may be changed and openings of other types employed where other con-

tents of a different nature are to be contained in the vessel and the structure of the annular compression rib is obviously applicable to my various closures and to the various forms of openings for access to the 40 contents of the vessel.

What I therefore claim and desire to secure by Letters Patent is:—

1. A closure for a containing vessel having a shoulder about its mouth comprising a cap having an opening therein, a laterally swinging cover unyieldingly pivoted to one side of said cap, said cover having a central 50 recess formed on its inner face, a pack located in said recess and adapted to compressibly cover said opening when said cover is in closed position and a spring locking lip on said cover and adapted to engage 55 said shoulder when said cover is in said closed position.

2. In combination with a vessel neck having a shoulder about its mouth, a laterally swinging cover pivoted on one side thereof 60 and a spring locking lip on said cover on the side thereof opposite to said pivot, said cover having a recess on its under face, a pack located within said recess and adapted to cover the mouth of the vessel, said spring 65 locking lip being adapted to compress said pack upon said vessel mouth when said cover is in closed position.

In testimony whereof, I affix my signature in presence of two witnesses.

EUGENE D. CHELLIS.
